United States Patent Office.

V. A. HACKER, OF KNOXVILLE, TENNESSEE.

Letters Patent No. 77,085, dated April 21, 1868.

IMPROVED SCRUBBER.

The Schedule referred to in these Letters Patent and making part of the same.

TO ALL WHOM IT MAY CONCERN:

Be it known that I, V. A. HACKER, of Knoxville, in the county of Knox, and State of Tennessee, have invented a new and improved Scouring and Cleaning-Instrument; and I do hereby declare that the following is a full, clear, and exact description thereof, which will enable others skilled in the art to make and use the same, reference being had to the accompanying drawings, forming part of this specification.

Figure 1 is a side view of my improved instrument.

Figure 2 is a top view of the same.

Similar letters of reference indicate corresponding parts.

My invention has for its object to furnish an improved instrument for use in cleaning and scouring floors, stairs, ceilings, windows, &c., which shall be simple in construction, convenient in use, and effective in operation; and it consists in the construction and combination of the various parts, as hereinafter more fully described.

A is the handle of the instrument, in the upper end of which is formed a socket, a^1 , for convenience in attaching a wooden handle when required. The other or lower end of the handle is branched, or has two arms, a^2 , formed upon it, of such a shape and length as to receive the brush, which is pivoted between the ends of the said arms a^2 , as shown in the drawings.

B is a brush, the wooden back of which is securely attached to the rod by which the said brush is pivoted to the said arms.

C is a block, of the same form and size as the back of the brush B. One end of the block C is hinged to the end of the back of the brush B, and its other end is secured to the other end of said brush by a hook or other convenient fastening.

D is a sponge, cut out into a suitable size and form to correspond with the block C, to which it is attached by sewing it to the said block through holes formed therein for that purpose. When the sponge has become worn from use, it can be easily removed, and replaced with a new one, by unhooking the block C, and turning it back upon its hinged end.

E is a concave perforated plate, made of such a size and shape as to correspond with and fit upon the sponge D.

To the central part of the perforated plate E is attached the lower end of the lever F, which is so bent, as shown in fig. 1, as to pass through a slot in the lower part of the handle A, where it is pivoted to said handle into such a position as to be readily operated by the hand that holds the said handle, so as to press the perforated concave plate E down upon the sponge D, and press out the water that may be in said sponge.

If desired, a spring, G, as shown in red in figs. 1 and 2, may be attached to the handle A, with its end resting in a groove in the lever F, to hold the plate E down upon the sponge D with sufficient force to keep the instrument in proper position while being used.

For convenience in turning the brush and sponge-blocks upon their pivoting-points, according as the brush or sponge is required to be used, a button, H, as shown in red in the drawings, may be attached to the side of the brush-block.

I claim as new, and desire to secure by Letters Patent—

1. The combination of the brush B, block C, and sponge D, with each other, and with the arms a^2 of the handle A, substantially as herein shown and described, and for the purpose set forth.
2. The perforated concave plate E and pivoted lever F, in combination with the slotted handle A, substantially as herein shown and described, and for the purpose set forth.

The above specification of my invention signed by me, this 15th day of February, 1868.

V. A. HACKER.
